RADIO COIL AND SWITCH ASSEMBLY

Chester L. Walker, Daniel R. Moatz, and William Russell Allen, 3d, Springfield, Mass., assignors to United American Bosch Corporation, Springfield, Mass., a corporation of New York

Application June 9, 1936, Serial No. 84,246

10 Claims. (Cl. 171—119)

This invention relates to radio apparatus and more particularly to an interstage coil and switch assembly comprising a band changing apparatus for "all wave" receivers capable of reception on other frequency bands as well as the broadcast band. The subject matter herein constitutes an improvement on a similar structure shown and described in the copending application of Chester L. Walker and Ken L. Henderson for "Radio coil and switch assembly", Serial No. 13,840; filed March 30, 1935. In such devices it has been found that the coils are not supported with sufficient rigidity to prevent vibration from occurring. The vibrations may arise from the action of the receiver loudspeaker or from other causes and result in adversely affecting the electrical characteristics of circuits including the coils.

An object of this invention, therefore, is to provide a unitary coil and switch assembly which is more reliable and efficient in operation.

Another object is to provide a coil and switch assembly which is more simple and economical in construction.

Still another object is to provide a coil and switch assembly which affords a more rigid and compact structure.

A further object is to provide a uncontrolled band changing assembly comprising a group of sectional units in which any unit is readily replaceable.

Other objects and advantages will in part be specifically set forth and in part be obvious when the following specification is read in connection with the drawings, in which:

Fig. 1 is a front view of the coil and switch assembly; Fig. 2 is a perspective view of the supporting bracket; and Fig. 3 is a simplified top plan view of a uncontrolled tandem assembly of individual coil and switch sections suitable for installation in a receiver.

Referring in more detail to Fig. 1 the numeral 1 indicates the front wall of the bracket shown in Fig. 2. The lugs 2 and 3 support a multi-pole rotary switch 4 of a well known type and comprising a rotary member 5 having a slot 6 to receive an operating shaft. The member 5 carries contacts 7 and 8 which cooperate with the terminals 9 mounted on the stationary member. The coil forms 10, 11, 12, and 13 are provided with the usual coil terminals comprising soldering lugs 14. The lugs 14 are soldered directly to the switch terminals 9 as shown and the coil forms are thus supported with a minimum of stray capacity and inductance. Such stray capacity and inductance as there is remains con-

stant under all conditions of handling and once compensated for need not again be considered. As shown in Fig. 3, a second multipole switch 4a is connected to the rear end of the coil forms in the same manner as the connections shown in Fig. 1. The trim and other compensating condensers are represented generally as 15 and are attached to the respective coil forms by soldering their terminals directly to soldering lugs carried by the coil forms.

Referring to Fig. 2, the front wall 1 of the bracket has extruded bosses 16 on the rear side thereof which are received within the front end of the coil forms to brace them against vibration or relative displacement. Each of the bosses 16 is provided with a key 16a which cooperates with a slot in the end of the associated coil form to comprise a positioning and locating means. Each key 16a is disposed at a different point on the circumference of the bosses 16 to insure that the proper coil is placed in its correct position in the assembly. The bracket has rearwardly extending web members 17 and 18 which connect the front wall 1 with an upright rear flange 19. The flange 19 has two arms terminating in lugs 20 and 21 which support a second multipole rotary switch 4a of the type shown in Fig. 1. A draw-bolt 22 is attached to the front wall 1 and carries a clamping plate 23 which contacts the rear end of the coil forms 12 and 13 of Fig. 1 to provide additional bracing against vibration.

In Fig. 3 is shown a simplified view of a complete uncontrolled coil and switch assembly for a superheterodyne receiver of the "all wave" type, embracing four separate wave bands. In receivers employing a single stage of radio frequency, an oscillator and a modulator, a set of coils is required for each stage. The letter A indicates a coil section serving the input or radio frequency stage, while B refers to an interstage coil section between the radio frequency amplifier and modulator. The oscillator coils are indicated as C. The front switch of each section is indicated as 4 and the complementary rear switches as 4a. A single control shaft 24 extends through the rotary members of all the groups of switches 4 and 4a and is arranged to be readily removable. By removing the shaft 24, any coil section, for example B, may be individually removed and replaced without disturbing the adjacent sections or wiring connections. When removed, all solder joints of each section are completely accessible, with the aperture in the front wall 1 affording ready access to the connections at the terminals of the front switch 4.

- as shown in Fig. 1. For the sake of simplification, the condensers 15 which normally overlie the coil forms 10, 11, 12, and 13, are not shown in Fig. 3. The front walls 1 extend above the 5 coils to provide shielding between sections A, B, and C, but additional shielding may be added in the form of a single shield cover for the entire assembly, or individual covers for each section if desired.
- 10 It will be seen that the structure herein shown and described is convenient for repair and replacement, has a minimum of solder joints, and has no wiring to become disarranged and alter stray capacities and inductances.
- 15 16 Many changes and modifications may be made by any one skilled in the art without departing from the spirit and scope of the invention as defined in the following claims.
- We claim:
- 20 1. In a multiple coil and switch assembly, a bracket, a pair of multipole switch members supported in spaced relation upon said bracket, a front wall on said bracket and having a plurality of projections extending from the rear side thereof, a plurality of coil forms carrying windings, means including said switch members for supporting said coil forms, and means including said projections for preventing relative displacement between said coil forms.
- 25 2. In a multiple coil and switch assembly, a bracket having a front wall, a pair of multipole switch members supported in spaced relation upon said bracket, a plurality of coil forms carrying windings, means for supporting said coil forms upon said switch members, and means on said front wall engaging one end of said coil forms to prevent relative displacement thereof.
- 30 3. In a multiple coil and switch assembly, a bracket having a front wall, a pair of multipole switch members supported in spaced relation upon said bracket, a plurality of coil forms carrying windings, means for supporting said coil forms upon said switch members in parallel axial alignment, and means on said front wall engaging one end of said coil forms to prevent relative displacement thereof.
- 35 4. In a multiple coil and switch assembly, a bracket having a front wall, a pair of multipole switch members supported in spaced relation upon said bracket, a plurality of coil forms carrying windings, electrical terminals on each coil form at either end thereof, means comprising said terminals for supporting said coil forms on said switch members, and means on said front wall engaging one end of said coil forms to prevent relative displacement thereof.
- 40 5. In a multiple coil and switch assembly, a bracket having a front wall, a pair of multipole switch members supported in spaced relation on said bracket, a plurality of coil forms carrying windings, electrical terminals at either end of said coil forms, means comprising said ter-

minals for supporting said coil forms on said switch members, and means extending rearwardly from said front wall to prevent relative displacement between said coil forms.

6. In a multiple coil and switch assembly, a bracket having an upwardly extending front wall and an upright rear flange spaced from said front wall, a multipole switch member secured to said front wall adjacent an aperture therein, a second multipole switch member secured to 10 said rear flange, and a plurality of coil forms jointly supported by said switch members and engaging a portion of said front wall.

7. In a multiple coil and switch assembly, a bracket having an upwardly extending front wall and an upright rear flange spaced from said front wall, a multipole switch member secured to said front wall adjacent an aperture therein, a second multipole switch member secured to said rear flange, a plurality of coil forms supported in 20 parallel axial alignment by said switch members whereby one end of said coil forms engages the rear side of said front wall, and clamping means extending rearwardly from said front wall and engaging the rear end of adjacent coil forms. 25

8. In a multiple coil and switch assembly, a plurality of independent aligned sections, each section comprising a bracket having a front wall, a pair of multipole switch members supported in spaced relation upon said bracket, a plurality of coil forms jointly supported by said switch members, means on said front wall engaging one end of said coil forms to prevent relative displacement thereof, and a common actuating means for simultaneously controlling the 30 switch members of all of said sections.

9. In a multiple coil and switch assembly, a plurality of independent aligned sections, each section comprising a bracket having a front wall, a pair of multipole switch members supported 40 in spaced relation upon said bracket, a plurality of coil forms jointly supported by said switch members, means extending rearwardly from said front wall engaging said coil forms and preventing relative displacement thereof, and a common actuating means for simultaneously controlling 45 the switch members of all of said sections.

10. In a multiple coil and switch assembly, a bracket having an upwardly extending front wall and an upright rear flange spaced from said front wall, a plurality of bosses on the rear side of said front wall, a locating means on each of said bosses, a plurality of tubular coil forms supported on said bracket with each receiving one of said bosses within an open end thereof, and means 50 on said coil forms cooperating with said locating means whereby a predetermined order of assembly is insured.

CHESTER L. WALKER.
